UNITED STATES PATENT OFFICE.

VINCENT J. CONCES, SR., OF EAST CHICAGO, INDIANA.

FLYING-MACHINE.

1,183,799.

Specification of Letters Patent.

Patented May 16, 1916.

Application filed October 13, 1915. Serial No. 55,700.

To all whom it may concern:

Be it known that I, VINCENT J. CONCES, Sr., a citizen of the United States, residing at East Chicago, in the county of Lake and State of Indiana, have invented new and useful Improvements in Flying-Machines, of which the following is a specification.

This invention relates to flying machines of the heavier than air class and of that particular type in which the machine is sustained in flight by the lifting or lifting and driving action of one or more propellers, and one of its objects is to provide a flying machine of the stated type embodying a novel organization and arrangement of propellers whereby the machine may be launched either directly into the air or in a manner similar to machines of the gliding type, and which may be made to hover over any given point and caused to ascend or descend in a straight path at any desired rate of speed.

A further object of the invention is to provide a construction and arrangement of lifting propellers and lifting and driving propellers, together with controlling mechanism, whereby the sets of propellers may be independently or conjointly thrown into and out of action at will, and whereby in the event of the incapacity of the lifting propellers the lifting and driving propellers will serve to sustain and drive the craft ahead, while in the event of the incapacity of the lifting and driving propellers the lifting propellers will serve to sustain the machine and adapt it to be controlled for a safe descent to the ground.

A further object of the invention is to provide means in the form of a steering propeller for dirigibly controlling the flight of the machine in a horizontal plane for lateral steering control, and further to provide means whereby the propelling devices may be governed to vary the speed of travel of the machine in both a vertical and in a horizontal plane and for controlling the machine to maintain the stability thereof.

With these and other objects in view, the invention consists of the features of construction, combination and arrangement of parts herein fully described and claimed, reference being had to the accompanying drawings in which:

Figure 1 is a front elevation of a flying machine embodying my invention. Fig. 2 is a top plan view of the same. Fig. 3 is a

vertical transverse section through the machine. Fig. 4 is an end elevation of the machine. Fig. 5 is a vertical longitudinal section taken on a line parallel with the longitudinal axis of the machine. Fig. 6 is a sectional plan view on the line 6-6 of Fig. 3. Fig. 7 is a sectional view on the line 7-7 of Fig. 3.

In carrying my invention into practice, I provide a frame 1 of suitable construction, and which includes a main frame portion 2 and head and tail portions 3 and 3', the frame as a whole being made of wood or metal or of composite material and consisting of upright and horizontal beams and connecting members and braces suitably fastened and reinforced. The central portion 2 of the frame is walled, as shown at 4 to provide a cabin or housing, said cabin or housing being subdivided by a horizontal partition 5 to provide compartments 6 and 7, the partition 5 forming the ceiling of the lower compartment 6 and floor of the upper compartment 7. The sides of these compartments may be provided with doors, windows or other suitably-closed openings to admit light and afford side observation, and these compartments may be entirely open at the front and rear or suitably closed, as may be desired in service. The lower compartment 6 is preferably designed for use as a pilot's and engine compartment and the upper compartment 7 for use as a passenger or freight carrying compartment, but their uses may be varied as circumstances may require. The central portion of the frame preferably has a depending extension 9 in which the compartment 6 is mainly formed, and this extension may be suitably constructed to stably support the machine when it rests upon the ground. If desired, the said extension may be equipped with wheels and skids or hydroplane floats to adapt the machine to be launched and landed like a gliding structure as well as to rest and travel upon the surface of a body of water and to be launched therefrom.

Journalized upon the central portion of the machine is a vertical drive shaft 10 receiving driving action from a motor 11. This shaft is constantly driven and in practice may be operated by a plurality of motors, so that in the event of the derangement of a motor or motors the shaft may still be driven by adequate power. At its upper end the shaft

10 carries gears 13 and 14 meshing with gears 15 and 16 on horizontal and longitudinally extending shafts 17 and 18 journaled respectively upon the main frame and head 15 and tail frames and respectively carrying at their front and rear ends beyond the head and tail frames sets of lifting and driving propellers 19 and 20, each set consisting of a pair of propellers arranged approximately 20 at an angle of 90° with relation to each other, each propeller preferably having a pair of diametrically disposed blades so that the blades of the two propellers will have a working arrangement at an angle of 90° to 25 each other. The blades of these propellers are dished or set at such an angle that, while the propellers of each set revolve vertically and in a direction transversely of the machine on a horizontal longitudinal axis, they 30 will exert both a lifting and a driving impulse. The two sets of lifting and driving propellers have sufficient lifting and driving power to maintain the craft in flight at a certain rate of speed and to govern it for 35 ascent or a safe descent as occasion may require. The gears 15 and 16 are feathered to slide upon and rotate with the shafts 17 and 18 and are adapted to be thrown into and out of engagement with the gears 13 and 14 by means of bell crank levers 13' and 14' coupled by connections 13^a and 14^a passing over suitable guides with control devices 13^b and 14^b, whereby the propellers may be independently or conjointly thrown 40 into and out of action at will without stopping the driving shaft.

Disposed within the spaces bounded by the tail frames 3 and 3' are sets of lifting propellers 21 and 22, each comprising a pair 45 of superposed propellers, the propellers of each pair having the same arrangement as the propellers of each set of lifting and driving propellers, and said propellers 21 and 22 being respectively mounted upon vertical shafts 23 and 24 arranged in parallel relation with and equidistantly from the central guide shaft 10. On the shafts 23 and 24 are gears 25 and 26 which mesh with gears 27 and 28 loosely mounted on a horizontal longitudinal transmission shaft 29 in gear with the drive shaft 10, as indicated 50 at 30. The gears 27 and 28 are feathered to slide upon and rotate with the shaft 29 and adapted to be thrown into and out of connection with the gears 25 and 26 by pivoted levers 27' and 28' coupled by connecting rods 27^a and 28^a, with control devices 27^b and 28^b, whereby the shaft 29 may be connected with or disconnected from the driving shaft 10 55 and the propeller shafts 23 and 24 thrown into and out of operation, independently or conjointly, at will. The propellers 21 and 22 are of a lifting capacity sufficient to sustain the weight of the loaded machine and 60 to lift it directly from the ground, and it

will thus be understood that the machine may be caused to directly ascend at any given speed and also to descend in a controlled manner, the speed of descent being regulated by varying the speed of the 70 lifting propellers.

In the operation of launching the machine either the lifting and driving propellers may be employed for a running and gliding ascent or the lifting propellers employed 75 for a direct ascent or these sets of propellers may be jointly used for a quick ascent combined with a driving ahead motion. When the machine reaches the desired altitude the speed of the lifting propellers may be governed to render them capable in conjunction with the lifting and driving propellers of sustaining the weight of the craft, so that the driving propellers will force the craft 80 ahead in horizontal flight. Whenever it is desired to cause the machine to hover or remain stationary in the air over any given point the lifting and driving propellers are thrown out of action and the lifting propellers operated with sufficient speed to sustain 85 the machine in the air.

If while in flight the lifting propeller should become incapacitated, the lifting and driving propellers will carry the machine and enable it to be controlled until a landing is made, and on the other hand if the lifting and driving propellers should become incapacitated the lifting propellers will sustain the weight of the craft and enable it to be landed at any desired and controlled 90 rate of speed. Inasmuch as the different propellers of the sets are also capable of being independently governed, it will be further understood that in the event of incapacity of the steering mechanism employed 95 the machine may be steered by controlling the propellers in an obvious way, and the described arrangement of the sets of propellers also enables the machine to be balanced 100 at all times with great reliability and efficiency. By disposing the sets of lifting and driving and the sets of lifting propellers at the stated points upon the machine frame, these propellers act to establish gyroscopic 105 forces which neutralize each other to maintain stability while opposing contrary air pressures or forces, thus keeping the machine 110 in full flight in a state of equilibrium.

In order to provide for the steering of the machine under all ordinary conditions a 115 steering propeller 31 is employed and mounted upon a shaft 32 arranged at right angles to the line of flight, said shaft being driven by chain and sprocket gearing 33 from an actuating shaft 34 connected by a drive 120 chain 35 with a gear 36 on a shaft 37 carrying a gear 38 adapted to mesh with a double gear 39 on the shaft 29. The gear 39 may consist, as shown, of spaced gear members fixed to a sleeve 39' feathered to slide 125

upon and rotate with the shaft 29, said gear being adjustable in opposite directions from a neutral position to bring one or the other of its gears into mesh with the gear 38, so that the direction of motion of the steering propeller may be reversed at will. The sleeve 39' is adjustable by means of a lever 40 coupled by a connecting rod 41 with a control device 42.

10 The steering propeller is arranged upon one of the lateral or side portions of the frame and when driven in one direction will have a driving action to turn the machine in one direction, and when driven in the opposite direction will operate as a tractor for a reverse steering operation, as will be readily understood. In the event that this propeller or its gearing should become inoperative from any cause the machine may be 15 steered and controlled in the manner above described.

I claim:—

1. A flying machine comprising a main frame including a central portion and head and tail portions, a vertical shaft upon the central portion of the frame, shafts extending longitudinally upon the head and tail portions of the frame in a direction parallel to the line of flight, and each carrying a 25 pair of driving and lifting propellers having a fixed angular relationship, means for independently or conjointly driving said propeller shafts from said vertical shaft, vertically disposed propeller shafts upon the 30 head and tail portions of the frame, each carrying a pair of superposed lifting propellers arranged to revolve within such portions of the frame, and means for independently or conjointly driving said vertical propeller shaft from the central vertical 35 shaft.

2. A flying machine comprising a main frame including a central portion and head and tail portions, a vertical shaft upon the

central portion of the frame, shafts extending longitudinally upon the head and tail portions of the frame in a direction parallel to the line of flight, and each carrying a pair of driving and lifting propellers having a fixed angular relationship, vertically disposed propeller shafts upon the head and tail portions of the frame, each carrying a pair of superposed lifting propellers arranged to revolve within such portions of the frame, connections for driving the respective propeller shafts from the central vertical shaft, and means for controlling the 50 respective connections.

3. A flying machine comprising a main frame including a central portion and head and tail portions, a vertical shaft upon the central portion of the frame, shafts extending longitudinally upon the head and tail portions of the frame in a direction parallel to the line of flight, and each carrying a 55 pair of driving and lifting propellers having a fixed angular relationship, means for independently or conjointly driving said propeller shafts from said vertical shaft, vertically disposed propeller shafts upon the 60 head and tail portions of the frame, each carrying a pair of superposed lifting propellers arranged to revolve within such portions of the frame, means for independently or conjointly driving said vertical propeller 65 shaft from the central vertical shaft, a steering propeller mounted to revolve vertically on a horizontal longitudinal axis mounted upon one of the said frame portions, and means for driving said steering propeller in 70 opposite directions from the said central vertical shaft.

In testimony whereof I affix my signature in presence of two witnesses.
